FLUSH CORNER METAL FRAME
CONSTRUCTION

Henry J. Bianco, Baltimore, Md., assignor to The Burch Company, Baltimore, Md., a corporation of Maryland

Application June 27, 1950, Serial No. 170,655

4 Claims. (Cl. 189—76)

1

The present invention relates to a metallic frame for window sash, doors, etc., and more particularly to a metal frame construction in which the corners are flush and devoid of recesses, cavities, etc.

The principles of the present invention are applicable to metal frame constructions in general, but for purposes of illustration and not by way of limitation, the same will be described in detail in connection with a window sash frame. With the foregoing in mind:

The principal object of the invention is to provide a metal frame structure which is quite rigid, and which can be manufactured to close tolerances by mass production methods.

Another object of the invention is to provide a flush corner frame structure that can be made from either rolled or extruded metal shapes, preferably aluminum alloy, and constructed in a minimum of time and with a minimum of waste of material.

Another object of the invention is to provide a frame constructed from relatively inexpensive channel-shaped sections and provided with a flush corner joint that presents a neat and pleasing appearance, devoid of recesses, cavities or depressions.

A further object of the invention is to provide an aluminum alloy sash frame adapted to be mounted in runways or guide rails formed of a similar metal, but which has incorporated therein bearing means for preventing galling or scuffing of the metal and which will reduce friction between the sliding parts.

A still further object of the invention is to provide a sash frame having bearing surfaces on its sides at the corner joints thereof for reducing sliding friction and wear in use.

Other objects and features of the invention will be apparent from the following description taken in conjunction with the accompanying drawings, in which:

Fig. 1 is a front elevational view of a miter jointed metal window sash constructed in accordance with prior methods;

Fig. 2 is a diagrammatic view illustrating the waste of material incident to the two saw-cuts required for each miter joint in the manufacture of the window sash shown in Fig. 1;

Fig. 3 is an elevational view of a metal window sash embodying the principles of the present invention;

Fig. 4 is a diagrammatic view illustrating the manner in which the pieces for the frame shown

2

in Fig. 3 may be cut, with one saw-cut and without waste of material;

Fig. 5 is a fragmentary perspective view illustrating the flush corner joint embodied in the window sash shown in Fig. 3;

Fig. 6 is a fragmentary sectional view of one corner of the sash taken on the line 6—6 of Fig. 5 and particularly illustrating the novel angle bracket comprising the present invention;

10 Fig. 7 is a vertical sectional view taken on the line 7—7 of Fig. 6;

Fig. 8 is a horizontal sectional view taken along the line 8—8 of Fig. 6;

15 Fig. 9 is a perspective view of one of the angle brackets employed in the new sash construction;

Fig. 10 is a view illustrating the manner of assembly of the sash shown in Fig. 3;

Fig. 11 is a fragmentary sectional view similar to Fig. 6, but illustrating a modification embodying bearing strips at the respective corners of the sash for reducing friction and wear; and

Fig. 12 is a perspective view of the bearing strips shown in Fig. 11.

It has been more or less conventional practice

25 heretofore to construct a metal window sash frame, such as shown in Fig. 1, from side members 11 and 12, a top member 13 and a bottom member 14, all bevelled at their ends to provide a miter joint at each corner of the frame. The frame members 11 to 14 are secured together by concealed angle brackets 15 with the aid of screws and rivets (not shown). The frame members 11 to 14 are cut from channel-shaped stock 16, Fig. 2; two saw-cuts disposed at an angle of 90° to each other being necessary, as indicated at 17 and 18, resulting in a substantial waste of the sawyer's time and in the waste of a triangular piece of stock indicated by the numeral 19.

The new sash construction, Fig. 3, includes

40 side frame members 20 and 21, a top frame member 22, and a bottom frame member 23. The frame members 20 to 23 are likewise formed from channel stock 24 illustrated in Fig. 4, but

45 only a single saw-cut 25 at right angles to the stock is necessary to provide the desired squared ends on any two pieces forming a corner joint of the sash frame, as will become apparent hereinafter. None of the material is wasted as an incident to cutting, other than that cut through by the saw blade, and the time and expense of labor in manipulating the saw and in handling the stock to produce a second cut for each corner joint is eliminated.

50 The frame members 20 to 23 are preferably formed from aluminum alloy strips, either rolled

or extruded, in view of the corrosion-resistant and easy-working properties of such material. However, any other metal suitable for the purpose can be used in lieu thereof.

The joints at the respective corners of the new sash are identical and a description of one will suffice for all. Thus, referring to Figs. 6 to 8, inclusive, the side frame member 20 is channel-shaped in cross-section and includes parallel flanges or side walls 26 and 27 interconnected along one edge by a transverse base wall or web 28. The top frame member 22 likewise comprises flanges 29 and 30 and an interconnecting base wall or web 31. The top member 22 is disposed at right angles to the side member 20, with the lower edges of the flanges 29 and 30 engaging the upper squared end of the side member 20, and with the squared end of the top member 22 flush with the outer surface of the wall 28 of said side member. That is to say, the flanges 29 and 30 are directly engaged with the ends of the flanges 26 and 27.

The frame members 20 and 22 are secured together in the relationship described by means of a true right angle bracket 33, which is also preferably formed of aluminum alloy, the bracket having a uniform width, indicated by the dimension A, Fig. 9, which is substantially equal to that of the width of the groove in the channel-shaped members 20 and 22. Four angle brackets 33 are required for a complete sash, as shown in Fig. 3. These angle brackets are preferably made by cutting the same from a bar of stock having webs disposed at 90° to each other and of the cross-sectional shape best illustrated in Fig. 6. The angle brackets 33 are preferably severed by a rotating saw wetted by a suitable cutting solution, so that the sides of the angle brackets are substantially smooth and free from burrs. Each bracket 33 has a short leg 34 and a relatively longer leg 35 disposed perpendicular thereto. The leg 35 is cut away or recessed on the outer face thereof at a region 36 extending inwardly from the outer end of said leg to a shoulder 37. The recessed or cut-away portion 36 has a depth or dimension B which is equal to the thickness of the transverse wall 28 of the side member 20. Thus, a projection 38 is formed on the leg 35 adapted to be disposed directly above the wall 28 of the frame member 20 and to have its outer face disposed flush with the adjacent squared end of the top member 22. The height of the projection 38 is indicated by the dimension C and in practice is made a few thousandths of an inch less than the depth of the channel in the top member 22. The portion of the leg 35 beyond the shoulder 37 has a dimension D which is substantially equal to the length of the other leg 34, indicated by the dimension E, so that the leg portion 34 engaged with the top member 22 is substantially equal in length to the leg portion 35 engaged by the side member 20.

The leg 34 has a hole 40 drilled therein and this hole may be threaded, if desired, to receive a screw 41 for fastening the outer face of the leg 34 in tight engagement with the inner surface of the wall 31 of the top member 22. The leg 35 has a hole 42 drilled therethrough, which may also be threaded, if desired, for the reception of a screw 43 for securing the outer face of the leg 35 in tight engagement with the inner surface of the wall 28 of the side member 20.

A drilled and countersunk hole 44 is formed in the wall 31 of the top member 22 at a prede-

termined distance from the squared end thereof so that it is aligned with the hole 40 in the angle bracket 33. The side member 20 also has a drilled and countersunk hole 45 formed in the wall 28 thereof at a predetermined distance from its end so that it lines up with the hole 42 in said bracket. The holes in the frame members 20 and 22 are located by placing said members in suitable jigs during the drilling and countersinking operation. Similarly, the holes 40 and 42 may be drilled in the angle brackets 33 by placing said brackets in a jig mounted on a drill press so that the holes in the legs 34 and 35 are correctly drilled to line up with the holes 44 and 45 in the top and side members 22 and 23, respectively. Thus, mass production methods may be employed throughout in the fabrication of the parts constituting the sash frame.

It will be understood that rivets may be used 20 in lieu of the screws 43 for fastening the angle brackets to the frame members 20 and 21 to speed assembly of the sash. In this connection, and 25 in order to further expedite assembly, a pair of angle brackets 33 may be preassembled with the side members 20 and 21, as illustrated in Fig. 10. A rectangular sheet of glass 46 having a strip of U-shaped gasket material 47 mounted thereon and extending around its entire periphery is positioned between the frame members 20 and 21, as shown, with the gasket inserted into the channels of said frame members as far as permitted by the beaded portions 48 of said gasket material. The sub-assembly of the glass 46 and frame members 20 and 21 is placed upon 30 a support (not shown) and then the top and bottom members 22 and 23 are aligned with the frame members 20 and 21 to receive the legs 34 of the angle brackets 33 and all of the parts are 35 clamped in position by clamping means (not shown) so that the screws 41 may be threaded into the angle brackets 33 to complete the assembly. The clamping fixture employed is such 40 that it holds the frame members 20 and 21 in square relation so that the resulting sash is true and the frame members 22 and 23 are drawn down tightly against the squared ends of the frame members 20 and 21. Alternatively, of course, the angle brackets 33 can be first attached to the top and bottom members 22 and 23 45 to form subassemblies, and these frame members applied to the glass 46, and the side members 20 and 21 thereafter applied to said glass. As is best shown in Figs. 7 and 8, the thickness of the bracket legs 34 and 35 is equal to about half the depth of the grooves in the frame members 20 and 22 in order to provide ample space for the reception of the gasket 47 and the corner of the glass 46.

It will be understood that the frame members 22 and 23 can be varied in length to suit the width of any window, and that the side members 20 and 21 can likewise be varied in length to suit a window of any height. Frame members of different lengths and widths may be sold in package form, if desired, and shipped in a knocked down condition and assembled to form sash frames of different size, if desired, at the place of use. Glass and gasket material for the window sash may be purchased locally, thereby reducing the danger of loss by breakage incident to shipment of completely assembled sash.

It will be apparent that the foregoing construction provides a metal sash frame which is extremely rigid and which presents a neat and pleasing appearance due to the flush corners pre-

vided by the novel angle brackets 33 employed therein.

Aluminum alloy sash are usually mounted in aluminum alloy frames, rails or guideways. In views of the poor bearing properties of the aluminum alloy, there is a tendency for the metal on either the sash or the guideways, or both, to gall or scuff, with the result that the sash may not slide freely with respect to the guideways. This possible objection can be avoided by incorporating anti-friction or bearing elements in the sash structure and Figs. 11 and 12 illustrate a modified form of the invention including such elements.

Fig. 12 is a perspective view of a bearing element 50 made of stainless steel or zinc, bent into the general shape of a right angle. The bearing element 50 comprises a horizontal leg portion 51 and a vertical leg portion 52. The horizontal leg 51 is provided with a hole 53 that registers with the hole 40 in the bracket 33. The size of the leg 34 of the brackets 33 is reduced slightly to compensate for the thickness of the bearing element 50, so that the legs 51 fit snugly between the bracket legs 34 and the inner surface of the wall 31 of the top frame member 22 and the inner surface of the corresponding wall of the bottom frame member 23. The legs 52 overlie the projections 38 of the brackets 33 and extend slightly beyond the ends of the frame members 22 and 23, so that they can slidably engage with a guide member 54 indicated in dot-and-dash lines.

Fig. 11 shows the bracket legs 35 secured to the side member 20 by rivets 55, and the bracket legs 34 secured to the top and bottom frame members 22 and 23 by screws 56. The parts are so dimensioned that the screws 56 pull the edges of the flanges of the frame members 22 and 23 tightly against the end of the side member 20, thus assuring a rigid and square sash structure. Obviously, if desired, screws can be substituted for the rivets 55.

The stainless steel or zinc bearing elements 50 are adapted to slidably engage with the rail 54, without causing any scuffing or galling thereof and permit free sliding movement of the sash relative to the rail. While Fig. 11 shows only two corners of the sash, it is to be understood that bearing elements are employed at all four corners of the sash.

The feature of a bearing strip to reduce the friction of a sliding window sash is also applicable to sliding screens and a screen embodying bearing strips is disclosed and claimed in my co-pending application, Serial No. 170,656, filed of even date herewith.

It will be understood that changes in the details of construction and arrangement of the parts constituting the sash structures disclosed herein may be made without departing from the principles of the invention or the scope of the annexed claims.

I claim:

1. In a sash frame, a pair of hollow frame members, each having squared ends and arranged at right angles to each other with the inner side of one frame member engaged with the squared end of the other frame member and with the squared end of said other frame mem-

ber flush with the outer side of said one frame member; an angle bracket having the legs thereof disposed one in each of said frame members; a bearing element including a portion disposed between one leg of said angle bracket and one of said frame members, and another portion extending to the exterior of the frame to form a bearing surface therefor; and means securing said frame members, bracket and bearing element in assembled relation.

2. In a sash construction, a generally channel-shaped frame member having a squared end; an angle bracket having one leg disposed in the groove of said frame member and the outer face of its other leg substantially flush with the squared end of said frame member; a bearing element including a portion disposed between the outer face of said one leg and said frame member and a portion at least partially overlying said outer face of said other leg; and means securing said bearing element and bracket to said frame member.

3. In a sash construction, a generally channel-shaped frame member having a squared end; an angle bracket having one leg disposed in said channel and the outer face of its other leg substantially flush with the squared end of said frame member; a bearing element including a portion disposed between the outer face of said one leg and said frame member and a portion at least partially overlying said outer face of said other leg, said other leg extending transversely beyond said frame member and being recessed to a predetermined depth on the outer face thereof beyond said frame member to provide a shoulder lying in substantially the same plane as the edges of the sides of said frame member; and means securing said bracket and bearing element to said frame member.

4. In a sash frame construction, two frame members each generally channel-shaped in transverse cross-section and having squared ends, said frame members being disposed at right angles to each other with their channels facing inwardly and with one squared end of one of said frame members engaged by the flanges of the other; an angle bracket substantially equal in width to the width of the channels in said frame members having one leg thereof disposed in the channel of said one frame member and its other leg disposed in the channel of said other frame member, said one leg having a projection thereon with the outer face of said projection disposed flush with the squared end of said other frame member; a bearing strip disposed between said bracket and one of said frame members and having a portion extending beyond said frame members to provide a bearing surface; and means securing the frame members, bracket and bearing strip in assembled relation.

HENRY J. BIANCO.
